POURING SPOUT AND CONTAINER

Filed Feb. 7, 1931

UNITED STATES PATENT OFFICE

HENRY BRUCKER, OF MAPLEWOOD, NEW JERSEY, ASSIGNOR TO AMERICAN ALUMINUM
WARE CO., OF NEWARK, NEW JERSEY, A CORPORATION OF NEW JERSEY

POURING SPOUT AND CONTAINER

Application filed February 7, 1931. Serial No. 514,080.

This invention relates in general to a pouring spout for containers of a type including a bottom or body portion hingedly connected to one wall of a discharge opening in the container and formed with resilient sector-shaped side wings concentric with the axis of hinging to frictionally engage the walls of said opening, so that the body portion normally serves as a closure for the opening and is adapted to be swung outwardly therefrom to serve as a pouring spout when it is desired to discharge the contents of the container through said opening. The side wings of the spout are usually divergent from each other away from the body portion so as to resiliently engage the walls of the opening to hold the spout in closed position and maintain a tight engagement with the walls of the opening when the spout is open.

One object of the present invention is to provide a novel and improved pouring spout of this character embodying novel and improved features of construction whereby the movement of the spout outwardly of the opening is positively limited to prevent the spout from being accidentally disengaged from the container as the spout is swung into open position.

Another object is to provide the side wings of the spout adjacent the edges thereof normally disposed within the container with integral shoulders stamped laterally outwardly from the side wings to engage the inner walls of the container to limit outward movement of the pouring spout.

A further object is to provide a novel and improved construction at the inner edges of the side wings to facilitate insertion of the pouring spout into the opening in assembling the spout upon a container.

Further objects are to provide a pouring spout of the general character described in which the side wings extend beyond the hinged end of the body portion so as to project into the opening in the container, and the wings have projections adjacent the hinged point to prevent the spout from pulling outwardly from the opening in the container when the spout is swung outwardly with the body portion at substantially right angles to

the wall of the container to which the spout is connected; to provide a pouring spout of the character described embodying novel and improved features of construction whereby the spout can be easily, quickly and economically stamped from one piece of metal, and can be easily and quickly assembled on a container, and to obtain other advantages and results as will be brought out by the following description.

Referring to the accompanying drawing in which corresponding and like parts are designated throughout the several views by the same reference characters,

Figure 1 is a fragmentary vertical sectional view through one end of the container having a pouring spout embodying my invention connected thereto and shown in closed position.

Figure 2 is a similar view showing the spout in open position.

Figure 3 is a sectional view on the line 3—3 of Figure 2.

Figure 4 is a composite section and elevation showing the manner of assembling the spout and container.

Figure 5 is a sectional view on the line 5—5 of Figure 2.

Figure 6 is a detached perspective view of the pouring spout.

Figure 7 is a view similar to Figure 2 showing a modified form of the invention.

Figure 8 is a sectional view on the line 8—8 of Figure 7, and

Figure 9 is a detached perspective view of the spout shown in Figure 7.

In the specific embodiment of the invention shown in the drawing, the reference character 1 designates a container of any suitable construction having a top or cover 2. A discharge opening 3 is formed in the top or cover 2, said opening being substantially rectangular in shape and provided at one end thereof with hinge notches 4 which form an injecting tongue 5 integral with the top or cover 2.

The pouring spout is preferably formed of sheet metal and includes a body portion or bottom 6 of substantially the same shape as the discharge opening 3 except that one end of the body portion is adapted to overlie the tongue 5 and the other end is provided with a

nose or extension 7. The body portion is preferably approximately the same width as the opening 3 and the sides thereof are provided with integral resilient wings 9 which diverge from each other away from the body portion as shown in Figure 6 of the drawing. At one end of the body portion 6 of the spout, the wings are extended to form hinge lugs 10, and the wings are preferably 10 sector-shaped and concentric with said end of the body portion. The free straight edges of the wings 9 are bent or curved inwardly toward each other at 11 so that they are spaced apart a distance substantially equal 15 to the width of the opening 3 in the container.

In assembling the spout upon the container, the hinge lugs 10 are inserted in the hinge notches 4 so that they lie against the inner wall of the container, after which the spout 20 is pushed with a swinging action about said hinge lugs inwardly of the opening, the curved edges 11 automatically guiding the wings into the opening and the wings being sprung toward each other as the spout is 25 pushed into the opening. The spout may then be opened or closed by swinging it about the hinge lugs 10 and hinge notches 4, using the nose 7 as a handle or finger-piece. During this action the arcuate edges 12 of the wings 30 engage one end of the opening opposite the hinge notches 4 so that the spout is accurately guided and held against such movement in the opening as would dislodge the lugs 10 from the notches. With such a construction 35 it is necessary to limit the outward swinging movement of the spout to an angular position, less than 90° to avoid the possibility of the lugs 10 being pulled outwardly from the hinge notches so as to disconnect the spout 40 from the container. For this purpose the wings 9 are provided adjacent the meeting of their inner edges and their arcuate edges 12 and within the boundaries of said wings, with outward projections 13 which are preferably 45 stamped from the wings to provide shoulders 14 projecting laterally from the planes of the wings and at substantially right angles thereto to engage the inner wall of the container as the spout is swung into open position as shown in Figures 2 and 5 of the 50 drawing. The projections preferably incline toward the planes of the respective wings as at 15 in the direction of the rear edges of the wings so that the projections 55 may easily slip past the side edges of the opening 3 as the spout is inserted into the opening. These projections can be conveniently formed by slitting the wings as at 16 and pressing portions of the wings at the 60 rear sides of the slits outwardly to form shoulders 14. With this construction, it will be observed that the shoulders 14 provide positive stops to limit opening swinging movement of the spout. To remove the spout 65 from the opening 3, the wings may be pressed

together to move the shoulders 14 away from the edges of the opening.

Where it is desired that the spout shall open into a position with the body portion 6 at substantially right angles to the wall of the container in which the opening 3 is formed, it is necessary to provide some means adjacent the hinging point of the spout to prevent the hinge lugs from being pulled from the hinge notches. For this purpose, I may utilize on each of the wings a projection 17 identical in construction with the projections 13, as shown in Figures 7, 8 and 9. These projections 17 are arranged adjacent the hinge lugs 18 so as to engage the inner side 80 of the wall of the container when the spout is swung into open position as shown in Figure 7 of the drawing. With this construction, the projections 13 limit pivotal movement of the spout into open position, while the projections 17 hold the hinged end of the spout against accidental disconnection from the container.

Many modifications and changes in the details of construction of the spout will appear to those skilled in the art without departing from the spirit or scope of the invention and therefore I do not desire to be understood as limiting myself in the construction and use of the invention, except as required by the following claims when construed in the light of the prior art.

Having thus described my invention, what I claim is:

1. The combination of a container having a discharge opening in a wall thereof, and a spout including a body portion to overlie said opening and hingedly connected at one end to said wall, said spout having resilient sector-shaped side wings concentric with the point of hinging of the spout to frictionally engage the walls of said opening, one of said wings having a projection within the boundaries of said wing and projecting laterally from the plane thereof at substantially right angles thereto formed with a shoulder to positively engage the inner side of said wall of the container to limit opening movement of the spout, said projection inclining from said shoulder toward the plane of the wing to permit said projection to slip past the wall of the opening as the spout is inserted into the opening.

2. The combination of a container having a discharge opening in a wall thereof, and a spout including a body portion to overlie said opening and hingedly connected at one end to said wall, said spout having resilient sector-shaped side wings concentric with the point of hinging of the spout to frictionally engage the walls of said opening, one of said wings having a slit and a portion of the wing pressed laterally outwardly from the plane of the wing adjacent said slit to form a shoulder at substantially right angles to the plane

- of said wing to positively engage the inner side of said wall of the container and limit opening movement of said spout.
3. The combination of a container having a discharge opening in a wall thereof, and a spout including a body portion to overlie said opening and hingedly connected at one end to said wall, said spout having resilient sector-shaped side wings concentric with the point of hinging of the spout to frictionally engage the walls of said opening, one of said wings having a slit and a portion of the wing pressed outwardly adjacent said slit to form a shoulder to positively engage the inner side of said wall of the container to limit opening movement of said spout, said pressed out portion inclining from said shoulder toward the plane of said wing to guide the shoulder past the wall of said opening as said spout is inserted into the opening.
4. The combination of a container having a discharge opening in a wall thereof, and a spout including a body portion to overlie said opening and hingedly connected at one end to said wall, said spout having resilient sector-shaped side wings concentric with the point of hinging of the spout to frictionally engage the walls of said opening, one of said wings having a polygonal projection stamped up within the boundaries of said wing with one side projecting laterally from the plane of said wing at substantially right angles thereto to positively engage the inner side of said wall of the container to limit opening movement of the spout.
5. The combination of a container having a discharge opening in a wall thereof, and a spout including a body portion to overlie said opening and hingedly connected at one end to said wall, said spout having resilient sector-shaped side wings concentric with the point of hinging of the spout to frictionally engage the walls of said opening, the portion of said wings adjacent the free straight edges thereof extending inwardly toward each other so as to easily slip past the side walls of said openings as the spout is inserted into the opening.
6. The combination of a container having a discharge opening in a wall thereof, and a spout including a body portion to overlie said opening and hingedly connected at one end to said wall, said spout having resilient sector-shaped side wings concentric with the point of hinging of the spout to frictionally engage the walls of the opening, said wings diverging from each other outwardly from said body portion to resiliently and frictionally hold the spout in closed and open positions, and the portions of said wings adjacent the free straight edges thereof being bent out of the planes of the wings toward each other so as to guide the wings past the side walls of said opening to facilitate insertion of the spout into the opening.
7. The combination of a container having a discharge opening in a wall thereof and notches at one end of the opening, and a spout including a body portion to overlie said opening and having sector-shaped side wings concentric with one end of said body portion to frictionally engage the walls of the opening, said wings being formed with hinge lugs at said end to engage said notches and pivotally connect said spout to said wall, one of said wings having a slit adjacent the corresponding hinge lug and a portion of the wing pressed laterally outwardly from the plane of said wing adjacent said slit to form a shoulder at substantially right angles to the plane of said wing to positively engage the inner side of said wall of the container and prevent disengagement of said hinge lugs from said hinge notches.
8. A spout for containers including a body portion having means at one end for pivotal connection to a wall of a container at one edge of a discharge opening, and sector-shaped side wings concentric with said end of the body portion to frictionally engage the side walls of such opening, one of said wings having a polygonal projection stamped up within the boundaries of said wing with one side projecting laterally from the plane of said wing at substantially right angles thereto to face and positively engage the inner side of said wall of said container and limit opening movement of said spout.
9. The combination set forth in claim 7 wherein said pressed out portion inclines from said shoulder toward the plane of the wing to guide the shoulder past the edge of said opening as the spout is inserted into said opening.
10. The spout set forth in claim 8 wherein said projection inclines away from said laterally projecting side toward the plane of the wing to guide the projection past the edge of said opening as the spout is inserted into the opening.
11. The combination of a container having a discharge opening in a wall thereof, and a spout including a body portion to overlie said opening and mounted to hinge at one end on one edge of said opening, said spout having resilient sector-shaped side wings concentric with the hinged end of said body portion to frictionally engage the walls of the opening, each of said wings having a polygonal projection stamped up within the boundaries of said wing adjacent said hinged end of the body portion with one side projecting laterally from the plane of said wing at substantially right angles thereto to positively engage the inner side of said wall of the container and prevent disengagement of said spout from said opening, said projection being inclined away from said laterally pro-

jecting side toward the plane of the wing to guide said projection past the edge of said opening as the spout is inserted into the opening, and one of said wings having means to engage the inner side of said wall to limit opening movement of the spout.

HENRY BRUCKER.
